UNITED STATES PATENT OFFICE.

JAMES K. CROWLEY, OF ANSONIA, CONNECTICUT.

TABLE FOR TINNING ZINC AND OTHER METALS.

SPECIFICATION forming part of Letters Patent No. 380,248, dated March 27, 1888.

Application filed August 20, 1887. Serial No. 247,412. (No model.)

To all whom it may concern:

Be it known that I, JAMES K. CROWLEY, a citizen of the United States, residing at Ansonia, in the county of New Haven and State of Connecticut, have invented certain new and useful Improvements in Tables for Tinning Zinc and other Metals; and I do hereby declare the following to be a full, clear, and exact description of the invention, such as will enable others skilled in the art to which it appertains to make and use the same.

My invention has for its object to produce a table for the above-described purpose which shall be simple in construction, easy to operate, and at the same time economical in cost and durable.

With these ends in view I have devised the novel construction of which the following description, in connection with the accompanying drawings, is a specification, numbers being used to denote the several parts.

Figure 1 is a perspective illustrating my improved table in use, the lower portion of the sheet of metal being broken away to show the construction of the table; and Fig. 2 is a cross-section corresponding therewith.

It is of course well understood by those familiar with the art that zinc and various other metals are tinned by the application of melted tin thereto, which is spread upon the surface of the foundation metal with a brush.

In applying the molten tin to zinc and other soft metals serious difficulty has heretofore been experienced, owing to the fact that the heat of the melted tin was at times sufficient to partially fuse the zinc or other foundation metal. This objection I wholly overcome by the novel construction of table, which I will now proceed to describe.

10 1 denotes frame-work by which the table is supported, which may be of any preferred construction.

20 2 denotes cross-pieces which are convexed from end to end, as clearly shown in the drawings.

30 3 denotes the inner side pieces, which are attached to the ends of the cross-pieces, 4 the bottom, and 5 the outer side pieces. The two sets of side pieces and the bottom form troughs on opposite sides of the bed. The latter consists of a series of slats, 6, which are secured to the cross-pieces.

The tables may of course be made of any suitable size.

Tinned zinc as ordinarily placed upon the market is prepared in sheets seven feet long by two and one-half to three and one-half feet wide. The tables, therefore, for preparing tinned zinc are made of just sufficient length so that the edges of the piece will pass over the inner side strips and the lower end will just reach the ends of the slats.

7 is a loose clamping-piece curved on its under side to correspond with the curvature of the table proper. This clamping-piece is operated by a cam-lever, 8, which, when turned to the position shown, clamps piece 7 down firmly upon the piece of metal.

It will be observed that the edges of the bottom in front of the table proper converge toward each other, and that the side pieces likewise converge, so that a spout is formed at the end. This is in order to convey the molten metal that does not adhere to the zinc or other foundation metal into a suitable receptacle 75 placed to receive it.

It will be noticed that the table is set at an incline, so that the waste metal will run off quickly. In use the sheet of metal to be tinned is placed upon the table and locked in position 8c by the clamping-piece and cam-lever. The molten metal is then poured upon it from a suitable ladle or hand-furnace and quickly laid on evenly with a suitable brush. The waste tin runs off into the troughs at opposite sides 85 of the table and over the lower end of the sheet of metal down upon the bottom, and is conveyed by the trough into the receptacle placed to receive it.

Should it be desired to tin the opposite side 9c of the sheet, it is changed end for end, thus reversing it, and the operation repeated as before. The exact shape and size of the slats which form the table proper are not of the essence of my invention.

It is of course required that they shall not be so large or so far apart as to permit the sheet of zinc or other foundation metal to sink in between them, and, on the other hand, it is necessary that there should be sufficient space 100 between them to permit free circulation of air, there being no bottom under the slats. The slats are preferably made round or half round, as shown in the drawings. In practice I have

obtained perfect results by making them an inch or an inch and a half in diameter at the widest place and have placed them about half an inch apart. This, however, is a matter that 5 may be safely trusted to the judgment of the builder or user.

In using my improved tables constructed as described I have obtained the most perfect results, and have experienced no difficulty 10 whatever from partial fusion of the foundation-sheet in applying the molten tin.

It will of course be understood that the details of construction may be varied to an almost unlimited extent without departing from the 15 spirit of my invention.

I claim—

1. A table for tinning sheet metal, consisting

of suitable frame-work, cross-pieces convexed from end to end, and a bed consisting of a series of rounded slats separated from each other 20 to permit free circulation of air under the sheet being tinned.

2. In a table for tinning sheet metal, the combination, with a bed made of slats and inclined from end to end and convexed from side 25 to side, of troughs at the sides of the bed and a spout at the lower end thereof, whereby waste metal is carried away.

In testimony whereof I affix my signature in presence of two witnesses.

JAMES K. CROWLEY.
